UNITED STATES PATENT OFFICE

123,130

DESIGN FOR A CAKE OF SOAP

Marshall Mundheim, New York, N. Y.

Application July 27, 1940, Serial No. 93,962

Term of patent 7 years

To all whom it may concern:

Be it known that I, Marshall Mundheim, a citizen of the United States of America, residing at New York city, county of New York, Borough of Manhattan, and State of New York, have invented a new, original, and ornamental Design for a Cake of Soap, of which the following is a specification, reference being had to the accompanying drawing, forming a part thereof.

I claim:

The ornamental design for a cake of soap, as shown.

MARSHALL MUNDHEIM.
